BOW SIGHT

Hilton C. Hamm, East Hampton, Conn.

Application June 26, 1947, Serial No. 757,289

3 Claims. (Cl. 33—46)

1

This invention relates to archery and particularly to a bow sight to aid in accurately sighting the bow at targets at different ranges.

An object of the present invention is to provide a bow sight which will enable the target and including a wide field surrounding the target to be kept in full view during the aiming of the bow and when releasing the arrow.

A feature that enables the above object to be accomplished is that the principal members forming the sighting device are transparent and preferably made of durable sheet material that will not discolor with prolonged exposure to sunlight.

Another object of the invention is to provide a sighting member having adjustable opaque sighting points thereon, the sighting member being itself adjustable in a direction normal to the direction of adjustment of the sighting points.

And finally it is an object of the invention to mount the supporting member of the sighting device adjacent the gripping portion of the bow in fixed position while permitting flexure of the bow during sighting.

With the above and other objects in view the invention may include the features of construction and operation set forth in the following specification and illustrated in the following drawing.

In the accompanying drawing annexed hereto and forming a part of this specification, I have shown the invention applied to a standard archery bow and disposed in position for a right handed individual but it will be understood that the invention can be otherwise embodied and arranged and that the drawing is not to be construed as defining or limiting the scope of the invention, the claims appended to this specification being relied upon for that purpose.

In the drawing:

Figure 1 is a perspective view of the central portion of a bow showing the sighting device in position thereon.

Fig. 2 is a front elevation of the sighting device.

Fig. 3 is a side elevation thereof.

Fig. 4 is a front elevation of a modified form of the invention, and

Fig. 5 is a side elevation of the form of the invention shown in Fig. 4.

In the above mentioned drawing there have been shown but two embodiments of the invention which are now deemed preferable, but it is to be understood that changes and modifications may be made within the scope of the appended claims without departing from the spirit of the invention.

Briefly, and in its preferred aspect, the invention may include the following principal parts: First, a supporting member for the sighting device attached in fixed position to the bow a short

2

distance above the gripping portion of the bow; second, a laterally adjustable member on the supporting member; and third, vertically adjustable sighting points mounted on said laterally adjustable member.

Referring more in detail to the figures of the drawing, there is shown a conventional or standard form of archery bow 10, the central portion, to which the sighting device is attached, only 10 being shown. The bow 10 is provided with a gripping portion 12 and an arrow plate 14 as is usual with bows of this type. Just above the plate 14 and mounted in fixed position on the back face of the bow is a supporting member 16 for the sighting device forming the present invention. This support 16 as shown is in the form of a narrow vertically disposed bar and has a screw 18 for rigidly securing its lower end 16 to the bow 10. The upper end of the support 16 is secured to the bow preferably by wrappings 20 of cord or tape to permit slight flexibility relative to the bow at this end of the support.

Laterally adjustable relative to the support 16 is the sighting member 22. This member 22 has 25 upper and lower horizontally extending arms 24 and 26, slotted as shown and adjustable relative to the support by screws or small bolts 28 extending through the slots in the arms of the sighting member 22 and through suitable holes provided in the support. The sighting member extends obliquely at a slight angle to the vertical and has an elongated slot 30 substantially throughout its length. This member 22 may and preferably is 35 of rigid durable material such as plastic, "Plexiglas" or other material available in sheet form and is transparent in order not to obscure any portion of the field surrounding the target. Adjustably positioned within the elongated slot 30 are sighting spots 32 preferably in the form of 40 small screws adapted to be readily tightened to maintain them in adjusted position. The angularity of the elongated slot 30 relative to the axis of the bow may be varied by individually clamping the upper and lower arms 24 and 26 to the 45 support 16 in different positions along their slots.

In Fig. 4 is shown a modified form of the invention in which a supporting member 36 is provided with an adjustable cross piece 38. The 50 supporting member 36 may be secured to a bow in the same manner as the supporting member 16 shown in Figs. 1 and 2. An elongated slot 40 extends substantially the entire length of the supporting member 36 to permit vertical adjustment of the cross piece 38. To attach the cross piece 38 to the supporting member 36 a screw 42, tightened by a winged nut, passes through the slot 40 and a slot 44 formed in the cross piece 38. The slot 44 is of sufficient length to permit a substantial transverse adjustment of the cross piece.

The cross piece 38 may preferably be made of transparent material similar to that used in making the member 22 shown in Figs. 1 and 2.

At one end of cross piece 38 is an opaque dot of small size 46 to form the sighting point. The material surrounding this point 46 is cut away to provide a substantially open sight. At the opposite end of the cross piece 38 is a circular portion within the center of which is provided an opaque point 48. Spots 46 and 48 may be small metal members attached to the cross piece 38 or may be formed by painting a small portion of one of the surfaces of the cross piece.

By vertical and lateral adjustments of the cross piece 38 relative to the supporting member 36, and reversal of the cross piece 38, either sighting point 46 or 48 may be adjusted for any range and wind conditions. Also either sighting point 46 or 48 enables the entire target and surrounding field to be in sight when the arrow is released.

I claim:

1. A bow sight comprising a supporting member adapted for attachment to a bow, a member having spaced apart horizontal slots therein, means connecting said last mentioned member to said supporting member by said slots whereby said last mentioned member may be adjusted laterally relative to said supporting member, said laterally adjustable member having a substantially vertical slot formed therein, and sighting points positioned adjustably along said vertical slot.

2. A bow sight comprising a supporting member adapted for attachment to a bow in fixed position, a transparent member having spaced apart horizontal slots therein, means connecting

said transparent member to said supporting member by said slots whereby said transparent member may be adjusted laterally relative to said supporting member, said transparent member having a substantially vertical slot formed therein, and opaque sighting points positioned adjustably along said vertical slot.

3. A bow sight comprising a supporting member adapted for attachment to a bow in fixed position, a U-shaped transparent member having a central vertical portion and short upper and lower horizontal portions at either end, said end portions having horizontal slots formed therein whereby said transparent member may be adjusted laterally relative to said supporting member, said transparent member having a substantially vertical slot formed along its central portion, and opaque sighting points positioned adjustably along said vertical slot.

HILTON C. HAMM.
